United States Patent Office

Des. 179,370
Patented Dec. 11, 1956

179,370

CREAMER OR SIMILAR ARTICLE

A. Baker Barnhart, New York, N. Y., assignor to Lucent Corporation, New York, N. Y.

Application May 21, 1956, Serial No. 41,552

Term of patent 14 years

(Cl. D44—21)

Fig. 1 is a top plan view of a creamer or similar article, showing my new design.

Fig. 2 is a side elevational view, partially in section, taken along line 2—2 of Fig. 1.

Fig. 3 is a rear elevational view.

I claim:

The ornamental design for a creamer or similar article, as shown and described.
